[57] CLAIM

The ornamental design for a weight lifting bar, as shown and described.

DESCRIPTION

FIG. 1 is a front perspective view of a weight lifting bar showing my new design;

FIG. 2 is another front perspective view thereof with the handles in alternate positions;

FIG. 3 is a front plan view thereof;

FIG. 4 is a top plan view thereof;

FIG. 5 is a bottom plan view thereof;

FIG. 6 is a side perspective view thereof with the handles in alternate positions; and,

FIG. 7 is a cross-sectional view thereof taken along line 7—7 in FIG. 3.

FIG. 1

FIG. 2

FIG. 3

FIG. 4

FIG. 5

FIG. 6

FIG. 7
